(57) **CLAIM**

The ornamental design for a manual dental pick design with an integrated barrel shaped handle, as shown and described.

DESCRIPTION

FIG. 1 is a front perspective view of a manual dental pick design with an integrated barrel shaped handle.

FIG. 2 is a front view of a manual dental pick design with an integrated barrel shaped handle.

FIG. 3 is a rear view of a manual dental pick design with an integrated barrel shaped handle.

FIG. 4 is a left side view of a manual dental pick design with an integrated barrel shaped handle.

FIG. 5 is a right side view of a manual dental pick design with an integrated barrel shaped handle.

FIG. 6 is a top view of a manual dental pick design with an integrated barrel shaped handle; and,

FIG. 7 is a bottom view of a manual dental pick design with an integrated barrel shaped handle.

The broken line in the drawings is included for the purpose of illustrating environmental structure and forms no part of the claimed design.
